Christy M. Del Mas, New York, N. Y., assignor to Michael P. Grace, New York, N. Y.

Application May 4, 1953, Serial No. 24,831

Term of patent 14 years

(Cl. D45—10)

To all whom it may concern:

Be it known that I, Christy M. Del Mas, a citizen of the United States of America, residing at city, county and State of New York, have invented a new, original, and ornamental Design for a Finger Ring for Holding Perfume, of which the following is a specification, reference being had to the accompanying drawing, forming part thereof.

The figure of the drawing is a perspective view of a finger ring for holding perfume embodying my new design.

The setting element and the mounting surface are of uniformly circular cross section throughout.

I claim:

The ornamental design for a finger ring for holding perfume, as shown and described.

CHRISTY M. DEL MAS.
